CLAIM

The ornamental design for a terminal assembly with a bimetal thermal protection plate for a power receptacle, as shown and described.

DESCRIPTION

FIG. 1 is a top, side perspective view of a terminal assembly with a bimetal thermal protection plate for a power receptacle showing our design;

FIG. 2 is a bottom, side perspective view thereof;

FIG. 3 is a side view thereof;

FIG. 4 is an opposing side view thereof;

FIG. 5 is an end view thereof;

FIG. 6 is an opposing end view thereof;

FIG. 7 is a top view thereof;

FIG. 8 is a bottom view thereof; and,

FIG. 9 is an environmental view of the terminal assembly with a bimetal thermal protection plate for a power receptacle shown with a power receptacle.

The broken lines shown herein are included to show portions of the article and environment that form no part of the claimed design.
